UNITED STATES PATENT OFFICE

EARL WENSLEY, OF CICERO, ILLINOIS, ASSIGNOR TO WESTERN ELECTRIC COMPANY,
INCORPORATED, OF NEW YORK, N. Y., A CORPORATION OF NEW YORK

SOUND OR VIBRATION TRANSMITTING APPARATUS

Application filed May 10, 1928. Serial No. 276,658.

This invention relates to sound or vibration transmitting apparatus, and more particularly to a device for damping the vibrations in sound transmitting apparatus.

5 Damping devices are known in the prior art which operate upon the principle of expelling air from the interstices between leaves of paper and again drawing air between the leaves by creating a vacuum upon separating the 10 leaves. Certain difficulties have been experienced, however, in providing a device of this type in which the numerous leaves act uniformly so that their total effect may be determined from their number and in which 15 the damping effect is uniform over the area of the damping device.

It is an object of this invention to provide a damping device having a high degree of efficiency and dependability and which may 20 be easily manufactured and assembled.

In accordance with the general features of the invention, an acoustic apparatus such as a telephone transmitter is provided with a damping device consisting of a plurality of 25 integrally interconnected annular leaves superimposed upon one another to form a ring which is agitated by connecting a vibrating member of the acoustic apparatus to an end leaf, thereby producing a damping effect 30 upon the vibrating member due to the compression and rarefaction of the air between adjacent leaves.

It is believed that a complete understanding of the apparatus may be had by referring 35 to the following description taken in conjunction with the accompanying drawing, in which

Fig. 1 is a fragmentary cross-sectional view of a telephone hand set having a sound or 40 vibration transmitting device employing a damping device embodying the features of the invention;

Fig. 2 is an elevational detail view showing a diaphragm withdrawn from a stationary 45 container to extend the damping device;

Fig. 3 is an elevational view of the damping device of Fig. 2 rotated through an angle of 90 degrees, and

Fig. 4 is an end view of the damping de- 50 vice.

The invention is illustrated in connection with a sound transmitting apparatus or telephone transmitter having a cup-shaped member 7 which supports a resistance varying unit. Firmly secured within the cup-shaped 55 member 7 is a rigid member 8 which is provided with a circular central opening over which a cap 9 is fitted which serves as an electrode and forms a cavity for retaining resistance varying material of any suitable 60 type, such as comminuted carbon particles. The lower end of the cavity is enclosed by a cone-shaped diaphragm 10 having a plane circular surface facing the cavity. Diaphragms, such as used in acoustic apparatus, 65 have a more or less marked natural period of vibration for one or more frequencies and when acted upon by impulses at or near these frequencies or their harmonics they will respond much more than at other frequencies. 70 Because of this natural frequency and the resultant inequalities of response between impulses of different frequencies, the diaphragm may disturb and distort speech waves when their frequency falls within the range of the 75 natural period of the diaphragm.

In order to reduce this maximum response at resonance to negligible proportions, a damping device 11 of paper or other suitable flexible material is interposed between the 80 rigid member 8 and the diaphragm 10. This damping device also serves to close the gap between the diaphragm and the rigid member 8 to retain the carbon particles within the cavity of the cap 9. The damping device 85 consists of a number of annular leaves alternately interconnected at opposite sides along a chord of the annulus. One of the end leaves is attached to the rigid member 8 by a suitable adhesive composition and the other 90 end ring is similarly attached to the diaphragm. When, during the vibration of the diaphragm, the diaphragm moves toward the damping device there will be a compression 95 of the air between the leaves accompanied by an expulsion of some of the air, and when the diaphragm moves away from the damping device the leaves will tend to separate, producing a rarefaction of the air between the 100 leaves accompanied by a movement of the air

to the damping device, which results in a restraining action upon the movement of the diaphragm tending to render it uniformly responsive to all frequencies.

5 The damping device 11 may be made in two parts each consisting of six leaves 12 without affecting the operating characteristics of the device. When the damping device is made in two parts, the end leaves of the assembly should be attached to the diaphragm and the rigid member by adhesive material as shown in Fig. 2. It has been found that when the damping device is made in one integral part it is not essential to attach the end leaves to the diaphragm and the rigid member, although this may be done.

10 It is an important feature of this invention that the air has free and uninterrupted access to the interstices between the leaves for a large part of the circumference of the annular leaves. This is due to that fact that the points at which the leaves are hinged alternate and the chord along which the hinge is formed, substends only an arc of substantially 15 thirty degrees of the periphery of a leaf. By constructing the leaves of the damping device of substantially uniform annular width around the entire periphery of the damping device, a uniform damping effect at all points 20 of contact with the diaphragm is insured. In Fig. 2, the rigid member 8 and the diaphragm 10 are shown disassembled with the end leaves of the damping device attached to these members and with the leaves of the 25 damping device extended showing them alternately interconnected at opposite sides. Such a damping device is easily handled without danger of disarranging the leaves and may be readily assembled with the leaves in 30 superposed position.

35 It will be understood that the embodiment of the invention herein described and illustrated is merely a convenient and useful form of the invention which is capable of many other modifications without departing from the spirit and scope of the invention.

40 What is claimed is:

1. In a transmitter, a diaphragm, and a damping device associated with the diaphragm comprising a plurality of annular leaves alternately interconnected on opposite sides.

50 2. In a transmitter, a diaphragm, and a damping device associated with the diaphragm comprising a plurality of leaves having a central opening and alternately interconnected on opposite sides by a hinged joint of less length than a dimension of the central opening.

55 3. In a transmitter, a diaphragm, and a damping device associated with the diaphragm comprising a plurality of leaves alternately interconnected at opposite sides by a short hinged joint.

60 4. In a transmitter, a vibratory element,

and a damping device associated with the vibratory element comprising a plurality of superimposed leaves alternately interconnected at opposite sides, more than one-half of the periphery of each leaf being free to move independently of other leaves.

65 5. In a vibratory apparatus, a vibratory element, and a damping device associated with the vibratory element comprising a plurality of circular leaves having a central 70 aperture, said leaves being alternately hinged on opposite sides along a chord of their circular periphery.

75 6. In a transmitter, a diaphragm, and a damping device associated therewith comprising a plurality of annular leaves having alternately interconnected portions on opposite sides, said interconnected portions being parallel to each other and normal to a diameter of the annular leaves.

80 7. In a transmitter, a diaphragm, a rigid member, and a damping device therebetween consisting of a plurality of integrally interconnected annular leaves.

85 8. In a transmitter, a diaphragm, a rigid member, a conical member containing comminuted resistance-varying material, and a plurality of superimposed interconnected annular leaves between the rigid member and the conical member for damping vibrative 90 responses of the diaphragm and for preventing leakage of the comminuted matter from the conical member.

95 In witness whereof, I hereunto subscribe my name this 27th day of April A. D. 1928.

100 EARL WENSLEY.
